UNITED STATES PATENT OFFICE.

CHARLES F. STODDARD, OF BOSTON, MASSACHUSETTS.

METHOD OF RECORDING MUSICAL TONES.

1,095,128.

Specification of Letters Patent.

Patented Apr. 28, 1914.

Application filed April 30, 1908, Serial No. 430,082. Renewed August 28, 1913. Serial No. 787,204.

To all whom it may concern:

Be it known that I, CHARLES F. STODDARD, a citizen of the United States, residing at Boston, in the county of Suffolk, Commonwealth of Massachusetts, have invented an Improvement in Methods of Recording Musical Tones, of which the following description, in connection with the accompanying drawings, is a specification, like letters 5 on the drawings representing like parts.

This invention relates to a method of recording a musical tone or group of tones; and as herein described it pertains more particularly to a method of recording one or 15 more characteristics of tones played upon a piano.

For purposes of illustration the invention may be described herein in connection with a preferred method and product which 20 respectively may be practised and produced conveniently by means of mechanism shown in the accompanying drawings, in which;

Figure 1 is a diagrammatic side elevation partly in section, of a detached key action 25 and one practicable illustrative form of recording means; Fig. 2, a detail view similar to that of Fig. 1, showing a key action at the moment of sounding a tone; Fig. 3, a view similar to Fig. 2, showing the 30 key action after a string has been struck and while it is still sounding; Fig. 4, a detail section on the line 4—4 of Fig. 1; Figs. 5, 6 and 7, diagrammatic views, showing different positions of illustrative key-controlled 35 means for governing the recorder; and Figs. 8 and 9 illustrate, respectively, forms of records embodying this invention.

It is to be understood, of course, that neither a method nor a product, embodying 40 features of this invention, is to be limited to the apparatus shown in the accompanying drawings, nor to the specific methods and records herein described to exemplify the various embodiments of which the invention 45 is susceptible.

For present purposes, an individual musical tone may be said to have three principal characteristics,—pitch, intensity and duration. The different tones of a group or 50 series have time relations, usually designated the “tempo” of a musical production.

It is an object of this invention, *inter alia*, to provide a method of representing sensibly, as for recording purposes, one or more 55 of the above suggested characteristics or qualities.

For convenience in explanation, a preferred method will be described in connection with the apparatus of Figs. 1, 2, 3 and 4.

Fig. 1 shows a typical key action in its normal position of rest. When the key A is struck it elevates a sticker B, rocking a hammer C and causing the latter to strike a string D, at the same time withdrawing 60 from the string a damper E. The striking position of the hammer C and the corresponding position of the damper E are shown in Fig. 2. So long as the key A is held depressed by the performer, after 65 striking the tone, the parts will remain in the position of Fig. 3, the damper E being removed from the string and the hammer C standing intermediate its striking position and its position of rest. This mode of behavior of a piano action may be utilized 70 conveniently in recording characteristics of the tone produced.

The amplitude of sound waves propagated by vibration of the string D defines the intensity of the tone, and depends upon the violence with which the hammer C strikes the string—that is to say, depends upon the dynamic force with which the string is struck. This force, according to fundamental 80 principles, depends upon the mass of the hammer C and its velocity upon striking the string. The mass is a constant for each of the hammer actions in a piano. The velocity involves the two elements of 85 distance and time,—the distance through which the hammer moves during its striking travel, and the time consumed in making this movement. As hereinafter described, it is preferred to employ only a part of this 90 travel of the hammer for recording purposes; but since the same length of travel is preferably always used, the distance element may be considered also a constant. Thus the time interval of hammer travel may be 95 the only variable involved in variations of 100 tone intensity. For any tone, therefore, this time interval supplies a convenient inverse measure of its intensity. To illustrate the present invention, a method will be described which employs this time measure in 105 representing intensities.

The duration of the usual tone depends upon the period of time after the string is struck, during which the damper E is held 110 away from the string; the tone beginning when the hammer strikes the string and

ending when the damper is returned to damp the vibration of the string. Thus a second time element affords a convenient measure for tone duration; and this measure is employed for illustration in the exemplary method described herein. The pitch of a tone depends upon which string is struck, and the illustrative method about to be described differentiates between tones of different pitches by suitably relating the records of the respective tones. The "tempo" of a composition depends upon the time relations of the different tone-sounding operations; and according to the illustrative method, the recording of the latter in proper relations serves also to record the tempo.

Referring again to Fig. 1, the hammer C has rigidly mounted upon it integral electrical contact points 10 and 11, arranged respectively to enter mercury baths 12 and 13. The mercury 12 is electrically connected through a battery 14, with a line 15 to a recording device; and the mercury bath 13 is electrically connected to the recording device by a line 16. When the piano action is at rest, as in Fig. 1, the contact point 11 stands above the surface of the mercury bath 13 and the circuit is broken, the contact point 10 being then deeply immersed in the bath 12. When the key rocks from the position in Fig. 1, toward that of Fig. 2, and preferably at some point during the latter part of the striking movement, the contact point 11 enters the mercury bath 13 and completes the circuit from the battery through the recording means, the mercury baths and the contact points 10 and 11. The closing of this circuit actuates the recording means to initiate a record. At the moment the hammer C strikes its string the contact point 10 is withdrawn from the mercury bath 12, and the circuit is again broken and the recording means rendered inactive to terminate its initial record. With this mode of operation, a record continues during preferably the latter part of the travel of the hammer to strike a string, when it has attained its full working velocity; and the time consumed during such travel may be indicated by the record, to represent the intensity of the tone. If the hammer accomplish the given travel in quick time—i. e. with a relatively great velocity—a loud tone results, as indicated by a short time record; if the hammer travel consumes more time—i. e. having less velocity—a tone of less intensity will be sounded and this will be indicated by a longer time record.

A convenient form of record, lending itself readily to the accurate ascertainment of represented intensities, consists of a straight line, the length of which may indicate by its linear units the interval of time ensuing between the first recorded po-

sition of the hammer and the final striking position. Thus a long line would indicate a slow moving hammer and a relatively soft tone; while a shorter line would indicate a swiftly moving hammer and a louder tone. 70

Figs. 1 and 4 illustrate recording means capable of making such a record as has just been suggested. This mechanism comprises a platen roll 20 which may have its surface covered with an imprinting medium such as 75 carbon paper. A supply of record receiving material R, such as a sheet of paper, may be wound upon a drum 22, passing thence over the platen 20 and beneath a feeding drum 24 and between the latter and a friction idler 26. 80 The feeding drum 24 may be rotated in any practicable manner, as by a worm and gear illustrated in Fig. 1. A constant speed of movement of the record receiving material R is best for the purposes of the specific 85 apparatus shown.

The inner face of the record sheet R, lying next the platen 20, contacts with the carbon paper thereon and receives the record. A stylus 28 rests normally upon the 90 record sheet R on the opposite side thereof from the carbon paper. An armature 30 of an electromagnet rests with its dead weight upon the upper end of the stylus 28. The combined weights of the stylus and armature are not sufficient to press the record sheet R against the carbon so as to make a mark thereon; but when said armature is magnetically actuated to add pressure to the stylus 28 the latter, by its pointed end, 100 presses the recording sheet R against the carbon and causes a mark to be made upon the sheet so long as the magnetic actuation of the armature continues.

The armature 30 is operated by an electromagnet 32 which is in circuit with the lines 15 and 16 and battery 14. Thus, so long as the circuit remains closed by the contact points 10, 11 being simultaneously immersed in their mercury baths, the magnet 110 32 will be energized, and the armature 30 attracted to depress the stylus 28, causing a mark to be recorded upon the record sheet R.

Each key action of a piano may be connected in the manner described with a magnet, to act upon its individual armature for depressing its individual stylus, each independently of the others; and for illustration a plurality of magnets 32 and 33 and armatures 30 and 34 are shown, conveniently 115 banked and nested, in Figs. 1 and 4, which show also the appropriate styli 28, 35 and 36.

With the arrangement described the first recorded point in the travel of a hammer C is preferably always the same and may be 125 advantageously the position of the hammer at the time when the damper leaves the string, the hammer having then acquired substantially its maximum working velocity. The time interval consumed in the 130

hammer travel is accurately recorded by the length of line made upon the record sheet between the first record point when the magnet is energized by closing the circuit, and the last recorded point preferably as the hammer strikes its string, at which the line ends upon breaking of the circuit.

The time interval of hammer travel may be measured in standard units of time by means of a suitable chronograph or the like. Comparison of such measurement with the corresponding recorded line will yield a linear unit accurately representative of a standard unit of time. With such a unit of measure the exact time represented by any recorded line may be ascertained, as in seconds. Also, the distance of hammer travel and the mass of the hammer can be readily measured. Having ascertained these constants, it is possible to ascertain the variable time factor for any tone in standard units by reference to the record; and by combining the two constant factors with the variable so determined, the exact force with which a string is struck may be calculated with mathematical accuracy. This process yields in terms of units of force, a force which may be used to reproduce with fidelity the "touch" employed in producing any particular tone.

While the extreme accuracy accessible as just described in the practice of a method embodying this invention, may be desirable in some cases, it suffices for usual commercial practices to represent merely the relative intensities of different tones of a performance, regardless of the absolute units of intensity, or factors determining intensity. It is practicable, therefore, to adopt an arbitrary grading of intensities such that all tones approximating certain intensities shall be classed in one grade; those approximating another intensity shall be classed in another grade; and so on. Thus using the specific illustrative record described, all recorded intensity lines approximating an arbitrary selected length may be graded as having an intensity equal to x ; those being recorded with lines approximating another length may be graded as having an intensity of y ; and so on. Thus, in reproducing intensities recorded as heretofore described, tones having recorded intensity lines of one class may be given all the same appropriate intensity.

Referring now to Fig. 8—there is shown a record such as may be made with the devices and by the method already described for illustration. The fragmentary record sheet there shown is assumed to be traveling toward the left, the left hand part of the sheet showing the initial record lines. The line 50 is started at the moment the electrical contact 11 enters its mercury bath and closes the circuit through the recording de-

vice; and this line continues until the electrical contact 10 emerges from its bath preferably at the instant the hammer C strikes the string. Thus the line 50 supplies a record of the time consumed by the hammer in traveling over its appointed distance; and therefore said line affords the convenient representation of intensity hereinbefore referred to. In like manner, the lines 51, 52, 53, 54 and 55 indicate the time of travel of other hammers in sounding other tones. For instance, the line 55 being very short indicates rapid travel of the hammer; and therefore a loud tone. For convenience in illustration, the various intensity record lines in Fig. 8, are graded from line 50, indicating the softest tone, to line 55, indicating the loudest.

When the string is struck the hammer C at once rebounds from the position of Fig. 2 to the position of Fig. 3, a short interval intervening between the withdrawal of the contact point 10 from its bath and its reinsertion upon the rebound of the hammer. This interval causes an interruption in the magnetic action on the recording stylus and leaves a gap 56 in the record. When, however, the hammer again closes the circuit the record line begins again and endures preferably until the damper E arrests the vibration of the string, as when the piano key is released, permitting the hammer action to resume the position shown in Fig. 1. In returning to this position, the contact point 11 is removed from its mercury bath and the record ceases. Thus, in addition to the line 50, the record of any given tone may comprise also a line 57, the right hand end of the latter in Fig. 8 indicating the end of a note. It will be remembered that the right hand end of a line 50 preferably indicates the instant at which the hammer C strikes the string, and initiates the sounding of a tone. Accordingly, the distance intervening between the right hand end of line 50 and the right hand end of a line 57 serves as a convenient measure or record of the duration of the tone.

As will be readily understood by those familiar with the art—the individual time values of the notes being indicated as just described; and the tones being recorded in proper sequence as they are played, by reason of the records being made immediately in response to the playing of the respective tones, the tempo of a composition is clearly indicated by the relations of the different lines appearing on the record, as in Fig. 8. The pitches of the different tones are also readily ascertainable by comparing the records with a keyboard; or by employing a suitable scale, provided if desired on the record sheet itself. Thus from a single record, such as is shown in Fig. 8, the characteristics of an individual tone or group of

tones may be ascertained with great accuracy.

In addition to the specific method and apparatus already described for illustration 5 the invention may be practised by means of such devices as are shown in Figs. 5, 6 and 7. Therein each key A' of a piano may be provided with a contact controlling device 60, arranged to play between contact 10 springs 61, 62. Said springs are insulated from each other except when both contact with a metallic connector 63. The spring 61 has connected to it a wire 64 which corresponds to the line 16 of Fig. 1; and the contact spring 62 has connected to it a wire 65, corresponding to the line 15 of Fig. 1, a battery being introduced into circuit with said wires and a recording device.

When the key A' stands in its normal inactive position shown in Fig. 5 the contact controller 60 holds the spring 61 out of contact with the connector 63 and thereby holds the recording circuit broken. When, however, the key is depressed to produce a 25 tone,—at some time during the travel of the key, preferably during the latter part, the spring 61 contacts with the connector 63 and completes the circuit to initiate a record as already described, thereby starting a line 30 70 shown in Fig. 9. Upon further depression of the key A' (see Fig. 7) the contact controller 60 strikes the spring 62 and again breaks the circuit and arrests the recording operation, thereby terminating the line 70. Thus the line 70 may serve as a record of 35 the time consumed by the movement of the key action between predetermined points—this time record serving as already suggested as a convenient representation of the 40 intensity of the tone.

The right hand end of the line 70 in Fig. 9 may represent approximately the time of striking the string. So long as the key is held depressed by the player the circuit remains broken; and during this time the tone continues to sound. When the key is released and the contact controller 60 moves upwardly the spring 62 contacts with the connector 63 and closes the circuit to initiate a line 71; and thereafter the key ascends to its normal inactive position and lifts the spring 61, again breaking the circuit and terminating the line 71. Thus the left hand end of the line 71 may indicate approximately the end of the tone; and the duration of the tone is indicated by the distance between the right hand end of the line 70 and left hand end of the line 71. In like manner the lines 80 and 81 may indicate singly and together the intensity and duration of another tone; also the lines 90 and 91, etc. The relations of these different lines in respect of sequence and arrangement may indicate tempo and pitch, as already described.

The preceding description and explanation will suffice to suggest the various embodiments of which the invention is susceptible. It is to be understood, of course, that the invention is not limited to the specific disclosure hereinbefore made; on the contrary, 70 as will appear to those skilled in the art, the specific methods and articles described for illustration may be variously changed and modified without departing from the proper scope of the subjoined claims. 75

Claims.

1. A method of making readable records indicative of the intensities of tones produced by a stringed musical instrument, which comprises recording upon a uniformly moving record-receiving sheet a plurality of parallel straight lines, one line for each tone to be recorded, each said line beginning at substantially the instant of undamping its corresponding string and terminating at substantially the instant of striking said string, whereby the length of each line so recorded graphically represents the elapsed time between the undamping and the striking of the corresponding string. 90

2. A method of making readable records indicative of the intensities of tones produced by a stringed musical instrument, which comprises recording upon a uniformly moving record-receiving sheet a plurality of parallel straight lines, one line for each tone to be recorded, said lines beginning at the same stages in the operations of their respective tone-sounding actions prior to the sounding of the respective tones, and each said line terminating at substantially the time at which its corresponding string is struck, whereby the length of each said line graphically represents the elapsed time between the first said stage and substantially 105 the time of striking the string. 95

3. A method of making readable records indicative of the intensities of tones produced by a stringed musical instrument, which comprises recording upon a record-receiving sheet which moves uniformly in relation to coöperating recording means, a plurality of parallel lines, one line for each tone to be recorded, said lines being so recorded during equal movements of their respective tone-sounding actions, and each said line terminating not later than the sounding of its corresponding tone, whereby the lengths of said lines represent graphically 110 the elapsed times during the said equal movements of their respective tone-sounding actions. 115

4. A method of making readable records indicative of the intensities of tones produced by a stringed musical instrument, which comprises recording in rectilinear alignment and along a record-receiving medium which moves uniformly in relation to 120 125

- coöperating recording means, a plurality of selected successive stages in the operation of a tone-sounding action, including, first, a stage prior to the sounding of the tone, and, 5 second, substantially the stage when the sound begins, whereby the linear distance between the records of said stages represents the elapsed time between said stages of operation.
- 10 5. A method of making readable records indicative of the intensities of tones produced by a stringed musical instrument, which comprises recording in rectilinear alinement along a record-receiving medium, 15 a plurality of selected successive stages in the operation of a tone-sounding action, including, first, a stage prior to the sounding of the tone, and, second, a subsequent stage not later than that at which the sound begins, whereby the linear distance between the records of said stages represents the elapsed time between said stages of operation.
6. A method of making readable records 20 indicative of the intensities of tones produced by a stringed musical instrument, which comprises recording, for each of a plurality of tones, in rectilinear alinement for each tone, the alinement for different 25 tones being parallel, a plurality of selected successive stages in the operation of a tone-sounding action, including, first, a stage prior to the sounding of the tone, and, second, a subsequent stage not later than that 30 at which the sound begins, whereby the linear distances between the first and second records for the respective tones, said distances being measured along parallel lines, 35 represent respectively in inverse proportion,
- the relative speeds of the tone sounding 40 actions.
7. A method of making readable records indicative of the intensities and durations of tones produced by a stringed musical instrument, which comprises recording in rectilinear alinement along a record-receiving medium, a plurality of selected successive stages in the operation of a tone-sounding action, including, first, the undamping of the string preparatory to sounding the same, 45 second, substantially the striking of the string, and, third, the damping of the string to terminate the sounding of the tone.
8. A method of making readable records indicative of the intensities and durations 50 of tones produced by a stringed musical instrument, which comprises recording along a record-receiving medium which moves uniformly in relation to coöperating means, a plurality of selected successive stages in the 55 duration of the tone sounding action for each of a plurality of tones to be recorded, including, first, a stage prior to the sounding of the tone, second, a subsequent stage 60 not later than that at which the sound begins, and, third, substantially the stage at which the sound ceases, the records of said three stages for each tone being alined and in parallelism to the corresponding records 65 for the other tones.
- In testimony whereof, I have signed my name to this specification, in the presence of two subscribing witnesses.
